(57) **CLAIM**

The ornamental design for an electrical quad box with four integrated plug covers substantially as shown and described.

DESCRIPTION

FIG. 1 is a top perspective view of an electrical quad box with four integrated plug covers showing our new design with two of four plug covers shown in a partially open position;

FIG. 2 is a top plan view thereof;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a top perspective view thereof showing the four plug covers shown in a closed position; and,

FIG. 9 is a top perspective view thereof showing the four plug covers shown in an open position.

The broken lines in the drawings represent unclaimed portions of the design.
